(57) **CLAIM**

The ornamental design for a combined dumbbell and base, as shown and described.

DESCRIPTION

FIG. 1 is a front, left and top perspective view of a combined dumbbell and base, showing my new design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an exploded view thereof; and,

FIG. 10 is an enlarged view of the portion labeled with numeric 10 in FIG. 1.

The evenly spaced broken lines in the drawings depict portions of the combined dumbbell and base that form no part of the claimed design. The dash-dot broken lines shown in FIGS. 1 and 10 are for the purpose of depicting the boundary lines of the enlarged views and form no part of the claimed design.
